UNITED STATES PATENT OFFICE.

JOHN B. FREYSINGER, OF NEW BRITAIN, CONNECTICUT, ASSIGNOR TO NORTH & JUDD MANUFACTURING COMPANY, OF NEW BRITAIN, CONNECTICUT.

BELT BUCKLE.

Application filed April 16, 1924. Serial No. 706,978.

My invention relates to belt buckles of the sheet metal type comprising two members to which the belt ends are respectively secured, and the primary object of the invention is to provide a simple and inexpensive construction whereby the two members may be detachably connected and will be effectually held against accidental disengagement while in use. A buckle embodying the invention is illustrated in the accompanying drawing, and the invention resides in certain novel features which will be hereinafter first fully described and then particularly pointed out in the appended claims.

15 In the accompanying drawings:

Figure 1 is a front elevation of the improved buckle;

Figure 2 is a rear elevation of the same;

20 Figure 3 is a sectional view showing the manner in which the buckle members are brought into engagement;

Figure 4 is a similar view showing the action in disengaging the members;

25 Figures 5 and 6 are detail views of the respective buckle members, and

Figure 7 is a sectional view showing the buckle members assembled.

The buckle members 1, 2 are struck from sheet metal and have a turned up rim or wall 3 around the entire extent of their edges on their rear sides. For convenience, the member 1 will be herein identified as the hook member and the member 2 will be called the slot member. The belt ends 4 may be secured to the belt members in any desired way, as by pivoted clamping devices 5, and the opposed edges of the members substantially abut when the members are interlocked or connected, as will be understood 40 on reference to Figure 1 of the drawing.

The hook member, 1, has a hook 6 at its forward edge which rises from and forms a continuation of the rim or wall 3. This hook may be a single hook approximately 45 coterminous with the rim or wall but I prefer, and have shown, two relatively short hooks arranged at opposite sides of and equidistant from the center of the rim. The hooks are slightly offset from the rim, as shown at 7, thereby producing a locking shoulder, and across the offset or shoulder a depression 8 is formed in each hook resulting in a cam rib or hump 9 in the bend or bight of the hook. The slot member 2 has a ledge or lip 10 extending laterally

from the rim or wall at its forward edge and a slot 11 is formed along the junction of the ledge and the rim, one wall of the slot being located in the ledge and provided centrally with a notch 12 while the opposite wall of the slot is located in the rim and is provided centrally with a locking nib or projection 13 mating with the notch 12. Depressions 14 are formed in the front side of the ledge adjacent the ends of the slot thereby forming projections 15 on the rear side of the ledge.

The width of the slot is only slightly greater than the cross section of the hook so that while the hook may be engaged through the slot there can not be any excessive play of the parts, and the nib or projection 13 will engage over the locking shoulder 7 when the members are connected. In closing the buckle, the hooks 6 are engaged through the slot 11 and the projections 15 bear against the inner surfaces of the respective hooks, as shown in Figure 3, to serve as fulcrums while the slot member is swung or turned toward the plane of the hook member. During this suggested turning movement, the ribs 9 act as cams against the opposed wall of the slot and draw the locking nib 13 into overhanging locking engagement with the shoulder 7, the metal of the ledge and the hooks possessing sufficient resiliency to yield to the locking nib as the latter rides over the rim into engagement with the shoulder. Some force must be applied, however, to cause the nib to ride into engagement with the locking shoulder and an equal force must be applied to release it from the shoulder, so that the buckle members will be effectually held against accidental disengagement while in use.

In opening the buckle, the free or outer edge of the ledge is caused to bear upon the inner side of the hook member, as shown in Figure 4, and constitutes a fulcrum about which the slot member is turned to force the nib 13 out of engagement with the shoulder 7 and then over the hooks.

Having fully described my invention what I claim as new and desire to secure by Letters Patent, is:-

1. A belt buckle comprising a substantially flat hook member having a hook on one edge and also having a transverse locking shoulder at the base laterally from the hook, and a slot member having a relatively nar-

110

- row slot through which the hook is engaged and a projection on the inner wall of the slot laterally from the hook-engaging portion thereof to frictionally engage and ride 5 across the locking shoulder on the hook member and to engage under the said locking shoulder on the hook member when the hook member is rocked toward the plane of the slot member.
10. 2. A belt buckle comprising a hook member having a hook at one edge, a slot member having a slot to receive said hook, a locking element on the slot member to frictionally engage the hook member, and fulcrum elements on the slot member to engage the hook member and effect release or engagement of said locking element as the slot member is turned in one or the opposite direction.
15. 3. A belt buckle comprising a hook mem-

ber having a hook at one edge, and a slot member having a slot to receive said hook, a locking element on one wall of the slot to engage the hook member, and a ledge on the slot member, said ledge being provided with 25 a fulcrum element to be engaged by the hook member and release said locking element.

4. A belt buckle comprising a hook member having a hook at one side edge and provided with a rib across the bight of 30 the hook, a slot member having a slot at one edge to receive the hook, a locking projection on one wall of the slot to engage the hook member, and a projection on the slot member adjacent the opposite wall of the 35 slot to fulcrum upon the inner side of the hook.

In testimony whereof, I have signed this specification.

JOHN B. FREYSINGER.
